UNITED STATES PATENT OFFICE.

JOHN R. HAMILTON, OF YONKERS, NEW YORK, ASSIGNOR TO SYPHO-CHEMICAL SPRINKLER CORPORATION, OF CROTON-ON-HUDSON, NEW YORK, A CORPORATION OF NEW YORK.

CHEMICAL FIRE-EXTINGUISHING APPARATUS.

1,264,391.

Specification of Letters Patent. Patented Apr. 30, 1918.

Application filed June 26, 1914. Serial No. 847,370.

To all whom it may concern:

Be it known that I, JOHN R. HAMILTON, a citizen of the United States, and resident of Yonkers, Westchester county, New York, have made a certain new and useful Invention Relating to Chemical Fire-Extinguishing Apparatus, of which the following is a specification taken in connection with the accompanying drawing, which forms part 10 of the same.

This invention relates especially to chemical or other pressure operated fire extinguishing apparatus in which the distributing system, preferably of the wet pipe type, 15 may have an upper portion substantially closed under emergency conditions and connected with the chemical mixing tank or other supply tank charged with extinguishing liquid preferably containing carbonate material. Coöperating chemical mixing means are arranged in connection with the tank and may comprise a siphon or other actuating device to be operated on the emergency condition of the system as by a suction connection with the upper portion thereof so as to operate the mixing means and render effective a predetermined charge of one of the chemicals so as to cause a predetermined working pressure in the chemical 25 tank sufficient to discharge the same from the distributing system on the fire for example. The action of this primary chemical mixing means may be made more effective by more quickly causing the mixture of chemicals which causes this initial working pressure and for this purpose the charge of chemical may first be delivered into a receiver from which it may be quickly discharged into the mixing tank as by the 30 automatic discharging action of the receiver, for example. Suitable supplemental mixing means or other pressure generating arrangements may be brought into action and automatically regulated to maintain the 35 predetermined initial working pressure substantially constant throughout the subsequent operation of the apparatus so that the extinguishing liquid is more effectively discharged at the point of danger.

50 In the accompanying drawings showing in a somewhat diagrammatic way a number of illustrative embodiments of this invention,

Figure 1 shows in vertical section one arrangement comprising a tipping chemical 55 container.

Fig. 2 shows another embodiment.

Fig. 3 shows still a further modification.

Figs. 4 to 7 are similar sectional views showing still other illustrative arrangements.

The distributing system may be of any desired construction and may as indicated comprise one or more risers or supply pipes 2 to which may be connected various distributing devices such as automatic sprinkler heads or hose connections which may as usual be located at different parts of the building to be protected. The distributing system may be of the wet pipe variety and 65 normally filled with water or other aqueous extinguishing liquid, such for instance, as a suitable solution of soluble and substantially inert salts to reduce the freezing point of the liquid for low temperature 70 work which should preferably be so selected as to be substantially inert or neutral to the other extinguishing liquid employed in connection with the system. The distributing system may be substantially closed 75 at its upper end as by the cap 3 which may have the reduced venting aperture 4 therein of pin-hole size which may furthermore be automatically closed by a check valve 104 or the like under emergency conditions, 80 if desired. The riser or supply pipe may be connected with the supply of extinguishing liquid 1 in any suitable way and may as indicated have its lower portion extend a considerable distance into the carbonate or other extinguishing liquid 17 in 85 this tank so as to extend adjacent the bottom thereof.

The mixing devices used in this connection may comprise any suitable automatically operated mixing means which are brought into action on the emergency condition of the system, as for instance when one of the automatic sprinkler heads opens and the extinguishing liquid is discharged 95 therefrom. The mixing means may as illustrated comprise a tipping acid container, such as 9, mounted eccentrically upon suitable pivots or trunnions 15 so as to tend to overturn and remain in inverted position 100 because of the weighted top 10 on this con-

tainer. Normally, however, the container is releasably held in the ineffective normal position illustrated by any suitable means, such as the lip 11, on the container with 5 which the actuating stem 8 may coöperate so as to normally hold the container in this position, while when the stem is withdrawn its emergency tipping action can take place. For this purpose a suitable actuating dia- 10 phragm such as 7, may be connected to the stem and arranged within a suitable casing or diaphragm chamber 6 which may be connected as by the suction connection 5 with the closed upper part of the distributing 15 system and preferably normally filled with extinguishing liquid so as to give a trouble indication in case any leakage or breakage occurs in this suction actuating connection. The container preferably comprises a pri- 20 mary chemical or acid chamber to contain either one of the chemicals which generate the working pressure in the system and a predetermined charge 13 of this acid or other chemical is placed in this primary 25 chamber so as to generate the desired predetermined initial working pressure when these mixing means operate on the tipping of the container. Under emergency conditions therefore the container quickly over- 30 turns and this initial charge of acid quickly acts on the carbonate liquor in the mixing tank 1 so as to generate the desired working pressure of 50 to 100 pounds more or less per square inch and deliver the extinguish- 35 ing liquid at this high pressure from any operating part of the system. This pressure is also communicated through its discharge pipe or connection 14 to the air space within the supplemental chemical or acid 40 chamber in which a supplemental and preferably larger supply of acid or other chemical 16 is arranged. Under these emergency conditions the container is in its overturned position so as to be inverted as compared 45 to what is shown in Fig. 1 and the air or other gaseous medium in the upper part of this supplemental chamber is compressed to substantially the working pressure within the mixing tank. Thereafter the feeding of 50 this chemical component becomes automatic and discharge from the supplemental chamber takes place whenever the pressure in the main mixing tank containing it falls appreciably so that enough acid is then dis- 55 charged by the greater pressure within the container to increase the pressure in the mixing tank by the resultant chemical action and cause a recompression of the fluid in the container. In this way the pre- 60 determined working pressure can be kept substantially constant throughout the discharge of the extinguishing liquid from the mixing tank provided the different chemicals are present in sufficient amounts.

65 Another arrangement is shown in Fig. 2

as comprising an automatically discharging tipping multiple container or receiver 22 which may as indicated be mounted on a pivot or pin 36 and be provided with a suitable counterweight 38 on the arm 37. This 70 counterweight normally holds the container in the full line position indicated, this normal position being determined by the stop 30 with which the container engages. A charge of pressure producing chemical 75 agent, such as 17, may be arranged in the mixing tank or chemical supply tank 1 connected to the distributing system in any desired way and a predetermined charge of the coöperating chemical or acid may be 80 poured into the primary chamber or compartment 23 of the tipping receiver so as to mainly stay therein, the surplus acid beyond the lower part of the discharge hole or aperture 101 running into the secondary com- 85 partment or chamber 26 so that these two parts 24, 25 of this initial charge of acid, for instance, are automatically proportioned between the two compartments, the greater amount being in the primary compartment 90 as illustrated. Any suitable actuating device which may include a siphon may be used to operate these chemical mixing devices and the siphon 27 may have its short leg 28 dipping into the primary compart- 95 ment of the receiver so that when operated it is adapted to transfer part or all of the contents thereof into the secondary compartment 26. This siphon may be actuated by any suitable means on the emergency condition of the system and an actuating connection or pipe 32 may communicate with the upper portion of this siphon and with a suitable diaphragm chamber 33 in which the diaphragm 34 may be arranged so as to 100 be raised when the liquid or other fluid is withdrawn from the top of this diaphragm through the suction actuating connection 35 which may, for example, communicate with the closed upper part of the distributing 110 system as previously described. Under these conditions when the system comes into emergency operation as by the opening of one or more of the automatic sprinkler heads the diaphragm is quickly drawn up, 115 drawing up chemical into both legs of the siphon so that the siphon is started and thereafter rapidly transfers the chemical 24 into the secondary compartment 26 of the receiver. This transferring action continues 120 until the turning moment of the receiver is increased sufficiently to overcome the action of the counterweight and the entire receiver then quickly swings around its pivot into the dotted position shown in Fig. 2 in which 125 the heavy counterweight rests against the stop 31. This movement causes the entire initial charge of chemical to be automatically discharged from the receiver so as to exert the desired pressure generating action 130

in the mixing tank and create the initial working pressure in the tank which has been determined upon. This pressure may be subsequently maintained as by the automatic 5 delivery of similar pressure generating acid or other chemical from the supplemental chemical chamber 18 having a discharge connection or pipe 19 so that portions of the chemical 21 are discharged from time to 10 time from the discharge end 20 of this pipe to keep up the working pressure in the mixing tank to substantially the predetermined value.

In the arrangement shown in Fig. 3 the primary chemical or acid chamber 40 is formed in the upper part of the compound container 39 which may be secured by its flanges to the upper part of the chemical mixing tank 1. The chemical mixing means 20 in this case may comprise the discharge device or passage 41 having its receiving throat 48 adjacent the bottom of the primary chemical chamber so as to discharge substantially all of the acid or other chemical 51 initially 25 placed therein in predetermined amount. This action may be initiated by the suction connection or pipe 45 connected to the upper part of the distributing system as indicated, preferably above the level of the extinguishing liquid in the system where a wet pipe system is used. The emergency operation of the system causes a suction or pressure reduction in this actuating connection so as to reduce the pressure in the receiver or chamber 42 and thus effect the discharge of the chemical 51 into this receiver, this action being promoted by the equalizing aperture 44 by which this primary chamber is placed in communication with the outside air. This chemical as soon as it accumulates in the receiver to a substantial extent and preferably when practically all of this initial charge of chemical has entered the receiver and the suction is broken in the 45 throat 48 forces open the pivoted or otherwise mounted check valve 46 so as to allow the passage of this predetermined charge of chemical through the discharge throat 47 into contact with the coöperating chemical 50 50 which may be a solution of sodium bicarbonate or other carbonate liquid when sulfuric or other acid is used in the primary chamber. In this case the supplemental chemical chamber 49 may be filled with the desired amount of similar acid or chemical 55 50 to that contained in the primary chamber and may be automatically discharged at intervals through the discharge connection or passage 52, 53 having its lower end 54 60 extending toward the bottom of the chamber so as to discharge substantially all of the chemical therefrom. The initial mixing in this way of substantially the predetermined amount of acid or other chemical 65 causes the desired initial working pressure

within the mixing tank in the manner described and this pressure may be subsequently maintained substantially constant throughout the subsequent discharge of extinguishing liquid from the mixing tank.

In the arrangement shown in Fig. 4 the initial charge of acid or other chemical 51 is shown as arranged in the primary chemical or acid chamber 56 preferably adjacent the top of the mixing tank 1. The siphon 75 discharge device or pipe 60 may coöperate with this primary chamber and have its discharge end 62 provided with a suitable check valve 63 to normally close the same. The suction actuating connection 61 with 80 this siphon effects the starting thereof under emergency conditions of the system by drawing up the acid or other chemical which tends to rapidly pass down the lower part of the siphon so as to open the check valve 85 more certainly because of its impact action and then discharge this chemical into the co-operating pressure producing chemical 17 in the mixing tank. It is in some cases desirable to arrange a suitable automatic closing device such as float valve 55 in this suction connection to automatically close the same in case any liquid rises in the pipe which is preferably made of relatively small cross-section to minimize the amount of 90 liquid which it can accommodate. In this way the desired initial working pressure is caused in the mixing tank and may be subsequently maintained by the automatic discharge of acid or other chemical 50 from 95 the supplemental chemical or acid chamber 57 through the discharge connection 58 which as indicated may extend adjacent the bottom of the chamber.

In the arrangement shown in Fig. 5 the primary chemical or acid chamber 65 may be formed in the upper part of the casing 64 supported in any desired way in the mixing tank 1. The initial charge of acid or other pressure producing chemical 51 may 105 be placed in this chamber and withdrawn therefrom at the proper time by any suitable actuating arrangement such as the actuating suction connection 69 communicating with the upper part of the distributing system or other means for creating a suction as previously indicated. On the emergency operation of the system the suction caused in this connection draws the acid 110 51 up into the siphon 68 so as to start the siphon action thereof, the acid or other chemical flowing down through the lower leg of the siphon and opening the check valve 71 so as to continuously discharge the acid into the automatically discharging tipping receiver 70. If desired a suitable equalizer aperture, such as 119, may be formed in the upper part of the primary chamber so as to equalize the air pressure 115 therein. When this suction action has taken 120 125 130

place to such extent that the desired charge of acid or other chemical has been delivered into the receiver the weight of this acid overbalances the counterweight 73 normally 5 engaging the support 74 and swings the receiver and counterweight about the pivot 75 on which they are mounted. This movement carries the parts quickly around into the dotted position indicated, the predetermined 10 charge of acid in the receiver being quickly delivered and mixed with the coöperating chemical 17 in the mixing tank and the check valve 71 being, if desired, positively closed at the same time by a closing device 15 72 which may be provided on the counterweight to engage and shut the check valve. In this way the initial pressure in the mixing tank may be quickly brought up to substantially a predetermined pressure and may 20 be thereafter maintained at substantially that amount by the intermittent feeding of acid or other chemical from the supplementary chemical chamber 66, the acid 50 or other chemical therein being intermittently delivered through the discharge connection 67 in the manner described.

In the arrangement shown somewhat diagrammatically in Fig. 6 the initial charge of acid or the like may be poured into the 30 primary chemical or acid chamber 79 so that part of this charge 51 is contained therein and part passes through the throat 120 and over the partition 121 in this container 76 so as to form the lower portion 83 of this 35 charge within the lower portion of the receiver 77. Under emergency conditions a suction or partial vacuum is caused in any desired way in the suction pipe 78 preferably of relatively small capacity which thus 40 reduces the pressure within the receiver 77 and sucks up the charge of acid 51 so that it flows over the partition 121 into this receiver, the trapped lower portion 83 of this 45 charge being simultaneously sucked up somewhat to correspond with the amount of suction exerted. This discharge of the portion 51 of the acid or other chemical may 50 be promoted by the equalizing connection 80 communicating with the top of this primary chamber 79 and having an automatically 55 opening check valve 81 controlling its inlet end 82. Under these conditions the check valve opens and air enters the primary chamber 79 so that the discharge of acid 60 therefrom continues until the level of the acid reaches the throat 120 whereupon air passes therethrough in sufficient quantities to reduce or break the vacuum in the receiver 77 which allows the comparatively 65 rapid descent of the chemical therein which also promotes this ingress of air through the throat 120. The result is that the larger part of this charge of acid which is then in the receiver 77 is quickly discharged therefrom into the mixing tank 1 so as to gene-

rate pressure therein in connection with the coöperating chemical or carbonate liquor 17. In this way the desired initial working pressure is created in the mixing tank to discharge the extinguishing liquid therefrom 70 and this working pressure may be subsequently maintained substantially constant by the automatic discharge of the acid or other chemical 50 from the supplemental chemical chamber 85 through the discharge 75 connection 84 in the manner previously described.

In the arrangement shown in the Fig. 7 the primary chemical or acid chamber 100 may be formed within the casing 86 secured 80 in any desired manner to the mixing tank 1 for instance. The actuating suction connection 87 may communicate with the discharge passage 89 arranged in this chamber or siphon discharging feeder through opening 90 of relatively small area as compared to the area of the discharge pipe 91 leading into the receiver 94 below. This automatically discharging receiver may be provided with an automatically discharging siphon 90 device comprising the discharge connection or conduit 93 and the coöperating siphon passage 92 substantially concentric therewith, if desired. Under emergency conditions therefore the pressure in the discharge 95 passage 89 is quickly reduced and the initial charge of acid or other chemical 50 is therefore drawn up into this passage so that it can be discharged through the pipe 91 into the receiver below the capacity of the primary chamber 100 being made sufficient to allow for the discharge of this material and preferably this siphon discharging action is promoted by a suitable equalizing venting passage 98 of small area which may be 100 formed in this chamber and automatically closed when desirable by a check valve such as 118 of any suitable description. This action continues until the acid has accumulated in the receiver 94 to such an extent as 110 to rise within the siphon connection up to the top of the discharge pipe 93 thereof which is preferably given such area as to then start the siphon discharge of this acid or other chemical into the coöperating carbonate or other chemical component 17 below, this siphon discharge action being continued until the entire predetermined charge of pressure producing chemical has become 115 effective, this action taking place quickly 120 and uninterruptedly because of the large area equalizing aperture 95 which may be formed in the upper part of this receiver. In this way the desired initial working pressure may be rapidly secured in the mixing tank and this may close the suction connection as by closing an automatic ball check valve or the like 88 arranged therein. The initial working pressure thus caused may be subsequently maintained automatically 125 130

by the automatic feeding into the mixing tank of additional amounts of acid or other chemical 51 from the supplemental chemical chamber 96 which may be arranged in 5 any way to coöperate with the mixing tank and be provided with a siphon discharge connection 97, for instance, extending toward the bottom of the chamber and arranged to automatically discharge the liquid therefrom when necessary to maintain the 10 working pressure substantially constant as previously described.

It is of considerable advantage to supply a measured charge of sulfuric acid or other 15 stable acid in this way to the mixing tank since the desired initial working pressure can be thus secured more certainly and definitely than when the sodium bicarbonate solution or other carbonate material is what is 20 used for the initial measured charge. It is also desirable to use suitable means to maintain substantially constant the effective strength of the acid that is to prevent its carbonate generating action being decreased 25 by dilution or other causes which often become of serious importance after the apparatus has been charged for months. For this purpose it is desirable to cover the surface of the acid where it is exposed to the air 30 or to the gaseous medium within the mixing tank or other parts of the apparatus with a thin film or layer of inert mineral oil or other impervious material 131 which may of course be considerably thinner than is indicated in Fig. 7, capable of preventing substantial absorption of moisture. For similar 35 reasons it is also desirable to have the acid containers formed or lined with material such as 132 which is substantially inert to the action of acid of the strength employed. Such protecting oil films or layers may therefore be applied to the upper surface of the acid 50 within the acid chamber 100 and within the discharge passage 89 around the central discharge pipe. For similar 40 reasons it is also desirable to use similar means to maintain the effective strength of the acid substantially constant in the other forms of apparatus described, 45 although moderate moisture absorption is not so important in such forms of the apparatus as render effective the entire charge of acid originally placed in the primary acid chamber or container as shown in Figs. 1, 50 55 2 and so forth.

This invention has been described in connection with a number of illustrative embodiments, parts, materials, and arrangements, to the details of which disclosure the 60 invention is not of course to be limited, since what is claimed as new and what is desired to be secured by Letters Patent is set forth in the appended claims:

1. In fire extinguishing apparatus, a wet 65 pipe distributing system having an upper

portion substantially closed under emergency conditions, a chemical mixing tank charged with carbonate extinguishing liquid and connected to said distributing system to supply extinguishing liquid thereto, chemical mixing means comprising a siphon and a suction actuating connection therefor communicating with the upper portion of said distributing system and operated on the emergency condition of said distributing system 70 to start said siphon, a receiver into which said siphon discharges and provided with an automatically starting siphon discharge to be operated when a predetermined charge has entered said receiver and discharge the 80 same therefrom to cause a predetermined working pressure in said mixing tank and automatically operating chemical mixing means comprising a chamber having an at least substantially closed top and a siphon 85 discharge connection extending adjacent the bottom of said chamber and communicating with said tank to maintain the predetermined working pressure substantially constant throughout the discharge of the extinguishing liquid from said tank. 90

2. In fire extinguishing apparatus, a wet pipe distributing system, a chemical mixing tank charged with carbonate extinguishing liquid and connected to said distributing 95 system to supply extinguishing liquid thereto, chemical mixing means comprising a siphon and an actuating connection therefor operated on the emergency condition of said distributing system to start said siphon, 100 a receiver into which said siphon discharges and provided with an automatically starting siphon discharge to be operated when a predetermined charge has entered said receiver and discharge the same therefrom to 105 cause a predetermined working pressure in said mixing tank and automatically operating chemical mixing means comprising a chamber having an at least substantially closed top and a discharge connection extending adjacent the bottom of said chamber and communicating with said tank to maintain the predetermined working pres- 110 sure substantially constant throughout the discharge of the extinguishing liquid from 115 said tank.

3. In fire extinguishing apparatus, a distributing system, a chemical mixing tank charged with carbonate extinguishing liquid and connected to said distributing system to supply extinguishing liquid thereto, chemical mixing means comprising a siphon and an actuating connection therefor operated on the emergency condition of said distributing system to start said siphon, a 120 receiver into which said siphon discharges and provided with an automatically starting siphon discharge to be operated when a predetermined charge has entered said receiver and discharge the same therefrom to cause 125

a predetermined working pressure in said mixing tank and automatically operating chemical mixing means to maintain the predetermined working pressure substantially constant throughout the discharge of the extinguishing liquid from said tank.

5 4. In fire extinguishing apparatus, a wet pipe distributing system having an upper portion substantially closed under emergency 10 conditions, a chemical mixing tank charged with carbonate extinguishing liquid and connected to said distributing system to supply extinguishing liquid thereto, chemical mixing means comprising a siphon and 15 an actuating device therefor communicating with the upper portion of said distributing system and operated on the emergency condition of said distributing system to start said siphon, a receiver into which said 20 siphon discharges and provided with an automatically starting siphon discharge to be operated when a predetermined charge has entered said receiver and discharge the same therefrom to cause a predetermined working 25 pressure in said mixing tank and means automatically operating to maintain the predetermined working pressure substantially constant throughout the discharge of the extinguishing liquid from said tank.

30 5. In fire extinguishing apparatus, a wet pipe distributing system, a chemical mixing tank charged with carbonate extinguishing liquid and connected to said distributing system to supply extinguishing liquid 35 thereto, chemical mixing means comprising a siphon and an actuating device therefor operated on the emergency condition of said distributing system to start said siphon, a receiver into which said siphon discharges 40 and provided with an automatically starting siphon discharge to be operated when a predetermined charge has entered said receiver and discharge the same therefrom to cause a predetermined working pressure in said 45 mixing tank and means automatically operating to maintain the predetermined working pressure substantially constant throughout the discharge of the extinguishing liquid from said tank.

50 6. In fire extinguishing apparatus, a wet pipe distributing system, a chemical mixing tank connected to said distributing system to supply extinguishing liquid thereto, chemical mixing means comprising a siphon 55 and an actuating device therefor operated on the emergency condition of said distributing system to start said siphon, a receiver into which said siphon discharges and provided with an automatically starting discharge 60 charge to be operated when a predetermined charge has entered said receiver and discharge the same therefrom to cause a predetermined working pressure in said mixing tank and means automatically operating to 65 maintain the predetermined working pres-

sure substantially constant throughout the discharge of the extinguishing liquid from said tank.

7. In fire extinguishing apparatus, a distributing system, a chemical mixing tank charged with carbonate extinguishing liquid and connected to said distributing system to supply extinguishing liquid thereto, chemical mixing means comprising a siphon and an actuating device therefor operated on the emergency condition of said distributing system to start said siphon, a receiver into which said siphon discharges and provided with an automatically starting siphon discharge device to be operated when a predetermined charge has entered said receiver and discharge the same therefrom to cause a predetermined working pressure in said mixing tank.

8. In fire extinguishing apparatus, a distributing system, a chemical mixing tank connected to said distributing system to supply extinguishing liquid thereto, chemical mixing means comprising a siphon and an actuating device therefor operated on the emergency condition of said distributing system to start said siphon, a receiver into which said siphon discharges and provided with an automatically starting siphon discharge device to be operated when a predetermined charge has entered said receiver and discharge the same therefrom to cause a predetermined working pressure in said mixing tank.

9. In fire extinguishing apparatus, a distributing system, a chemical mixing tank connected to said distributing system to supply extinguishing liquid thereto, chemical mixing means comprising a siphon and an actuating device therefor operated on the emergency condition of said distributing system to start said siphon, a receiver into which said siphon discharges and provided with an automatically starting discharge device to be operated when a predetermined charge has entered said receiver and discharge the same therefrom to cause a predetermined working pressure in said mixing tank.

10. In fire extinguishing apparatus, a wet pipe distributing system having an upper portion substantially closed under emergency conditions, a chemical mixing tank charged with carbonate extinguishing liquid and connected to said distributing system to supply extinguishing liquid thereto, chemical mixing means comprising chemical feeder and a suction actuating device therefor communicating with the upper portion of said distributing system and operated on the emergency condition of said distributing system to start said feeder, a receiver into which said feeder discharges and provided with an automatically starting siphon discharge device to be operated when a predetermined charge has entered said receiver and discharge the same therefrom to cause a predetermined working pressure in said mixing tank.

terminated charge has entered said receiver and discharge the same therefrom to cause a predetermined working pressure in said mixing tank and automatically operating 5 chemical mixing means comprising a chamber having an at least substantially closed top and a discharge connection extending adjacent the bottom of said chamber and communicating with said tank to maintain 10 the predetermined working pressure substantially constant throughout the discharge of the extinguishing liquid from said tank.

11. In fire extinguishing apparatus, a distributing system, a chemical mixing tank 15 charged with carbonate extinguishing liquid and connected to said distributing system to supply extinguishing liquid thereto, chemical mixing means comprising a chemical feeder and a suction actuating device 20 vice therefor operated on the emergency condition of said distributing system to start said feeder, a receiver into which said feeder discharges and provided with an automatically starting siphon discharge device to be 25 operated when a predetermined charge has entered said receiver and discharge the same therefrom to cause a predetermined working pressure in said mixing tank and automatically operating chemical mixing means 30 comprising a chamber having a substantially closed top and a discharge connection extending adjacent the bottom of said chamber and communicating with said tank to maintain the predetermined working pressure substantially constant throughout the 35 discharge of the extinguishing liquid from said tank.

12. In fire extinguishing apparatus, a distributing system, a chemical mixing tank 40 connected to said distributing system to supply extinguishing liquid thereto, chemical mixing means comprising a chemical feeder and a suction actuating device therefor operated on the emergency condition of said 45 distributing system to start said feeder, a receiver into which said feeder discharges and provided with an automatically starting siphon discharge device to be operated when a predetermined charge has entered 50 said receiver and discharge the same therefrom to cause a predetermined working pressure in said mixing tank and automatically operating chemical mixing means comprising a chamber to maintain the predetermined working pressure substantially constant throughout the discharge of the extinguishing liquid from said tank.

13. In fire extinguishing apparatus, a distributing system, a chemical mixing tank 60 connected to said distributing system to supply extinguishing liquid thereto, chemical mixing means comprising a chemical feeder and a suction actuating device therefor operated on the emergency condition 65 of said distributing system to start said

feeder, a receiver into which said feeder discharges and provided with an automatically starting discharge device to be operated when a predetermined charge has entered 70 said receiver and discharge the same therefrom to cause a working pressure in said mixing tank and automatically operating chemical mixing means comprising a chamber to maintain the predetermined working pressure substantially constant throughout 75 the discharge of the extinguishing liquid from said tank.

14. In fire extinguishing apparatus, a distributing system, a chemical mixing tank connected to said distributing system to supply extinguishing liquid thereto, chemical mixing means comprising a chemical feeder and a suction actuating device therefor 80 operated on the emergency condition of said distributing system to start said feeder, 85 a receiver into which said feeder discharges and provided with an automatically starting siphon discharge device to be operated when a predetermined charge has entered said receiver and discharge the same therefrom to cause a predetermined working pressure in said mixing tank. 90

15. In fire extinguishing apparatus, a distributing system, a chemical mixing tank connected to said distributing system to supply extinguishing liquid thereto, chemical mixing means comprising a chemical feeder and a suction actuating device therefor 95 operated on the emergency condition of said distributing system to start said feeder, 100 a receiver into which said feeder discharges and provided with an automatically starting discharge device to be operated when a predetermined charge has entered said receiver and discharge the same therefrom to cause a working pressure in said mixing tank. 105

16. In fire extinguishing apparatus, a wet pipe distributing system having an upper portion substantially closed under emergency conditions, a chemical mixing tank 110 charged with carbonate extinguishing liquid and connected to said distributing system to supply extinguishing liquid thereto, chemical mixing means comprising a siphon and a suction actuating device therefor communicating with the upper portion of said distributing system to start said siphon under emergency conditions and render effective a predetermined charge of one of the chemicals and cause a working pressure in 115 said mixing tank and automatically operating chemical mixing means comprising a chamber having an at least substantially closed top and a siphon discharge connection extending adjacent the bottom of said chamber and communicating with said tank to maintain the predetermined working pressure substantially constant throughout 120 the discharge of the extinguishing liquid from said tank. 125

17. In fire extinguishing apparatus, a wet pipe distributing system having an upper portion substantially closed under emergency conditions, a chemical mixing tank 5 connected to said distributing system to supply extinguishing liquid thereto, chemical mixing means comprising a siphon and a suction actuating device therefor communicating with the upper portion of said distributing system to start said siphon under emergency conditions and render effective a predetermined charge of one of the chemicals and cause a working pressure in said mixing tank and automatically operating 10 chemical mixing means to maintain the predetermined working pressure substantially constant throughout the discharge of the extinguishing liquid from said tank.

18. In fire extinguishing apparatus, a wet 20 pipe distributing system, a chemical mixing tank connected to said distributing system to supply extinguishing liquid thereto, chemical mixing means comprising a siphon and an actuating device therefor communicating with said distributing system to start said siphon under emergency conditions and render effective a predetermined charge of one of the chemicals and cause a working pressure in said mixing tank and automatically operating 25 chemical mixing means to maintain the predetermined working pressure substantially constant throughout the discharge of the extinguishing liquid from said tank.

19. In fire extinguishing apparatus, a distributing system and connected pressure operated supply tank charged with carbonate extinguishing liquid, an acid chamber charged with sulfuric acid, means to prevent 30 variation in the effective strength of said acid by moisture absorption, coöperating acid feeding means comprising a siphon operated on the emergency condition of said system to discharge a predetermined charge of said acid into said tank and create the initial working pressure in said tank and automatic means comprising an acid chamber having a substantially closed top and a siphon discharge connection extending toward the bottom of said chamber and communicating with said tank to maintain said working pressure in said tank during the withdrawal of liquid therefrom.

20. In fire extinguishing apparatus, a 40 distributing system and connected pressure operated supply tank charged with carbonate extinguishing liquid, an acid chamber charged with sulfuric acid, means to prevent variation in the effective strength of said acid, coöperating acid feeding means comprising a siphon operated on the emergency condition of said system to discharge a predetermined charge of said acid into said tank and create the initial working pressure in said tank and automatic means

to maintain said working pressure in said tank during the withdrawal of liquid therefrom.

21. In fire extinguishing apparatus, a distributing system and connected pressure 45 operated supply tank charged with carbonate extinguishing liquid, an acid chamber charged with sulfuric acid, means to prevent variation in the effective strength of said acid, coöperating acid feeding means operated on the emergency condition of said system to discharge a predetermined charge of said acid into said tank and create the initial working pressure in said tank and automatic means to maintain said working 50 pressure in said tank during the withdrawal of liquid therefrom.

22. In fire extinguishing apparatus, a distributing system and connected pressure 55 operated supply tank charged with carbonate extinguishing liquid, an acid chamber charged with sulfuric acid, coöperating acid feeding means operated on the emergency condition of said system to discharge a predetermined charge of said acid into said tank and create the initial working pressure in said tank and automatic means to maintain said working pressure in said tank during the withdrawal of liquid therefrom.

23. In fire extinguishing apparatus, a distributing system and connected pressure operated supply tank charged with carbonate extinguishing liquid, an acid chamber and coöperating chemical mixing means operated on the emergency condition of said system to discharge a predetermined charge of acid of definite effective strength into said tank to create the initial working pressure therein and automatic means comprising an acid chamber having a substantially closed top and a siphon discharge connection extending toward the bottom of said chamber and communicating with said tank to maintain said working pressure in said tank during the withdrawal of liquid therefrom.

24. In fire extinguishing apparatus, a distributing system and connected pressure operated supply tank charged with carbonate extinguishing liquid, an acid chamber and coöperating chemical mixing means operated on the emergency condition of said system to discharge a predetermined charge of acid into said tank to create the initial working pressure therein and automatic means comprising an acid chamber having an at least substantially closed top and a discharge connection extending toward the bottom of said chamber and communicating with said tank to maintain said working pressure in said tank during the withdrawal of liquid therefrom.

25. In fire extinguishing apparatus, a distributing system and connected pressure operated supply tank charged with carbonate extinguishing liquid, an acid chamber

- and coöperating chemical mixing means operated on the emergency condition of said system to discharge a predetermined charge of acid into said tank to create the initial 5 working pressure therein and automatic means comprising an acid chamber having an at least substantially closed top to maintain said working pressure in said tank during the withdrawal of liquid therefrom.
- 10 26. In fire extinguishing apparatus, a distributing system, a connected chemical mixing tank charged with carbonate extinguishing liquid, chemical means comprising an acid chamber containing a charge of sulfuric acid covered with a protecting layer of inert oily material, a coöperating actuating device operated on the emergency condition of the system to discharge said acid and an automatically starting receiver into which said 15 acid is discharged to automatically discharge a predetermined charge of said acid into said carbonate liquor to cause the initial working pressure in said mixing tank and automatic chemical mixing means to there- 20 after maintain the working pressure substantially constant.
- 25 27. In fire extinguishing apparatus, a distributing system, a connected chemical mixing tank charged with carbonate extinguishing liquid, chemical means comprising an acid chamber containing a charge of sulfuric acid covered with a layer of inert protecting material, a coöperating actuating device operated on the emergency condition of the 30 system to discharge a predetermined charge of said acid into said carbonate liquor to cause the initial working pressure in said mixing tank and means to thereafter maintain the working pressure substantially constant.
- 35 28. In fire extinguishing apparatus, a distributing system, a chemical mixing tank charged with carbonate liquid and connected to said distributing system to supply extin- 40 guishing liquid thereto, chemical mixing means comprising an acid chamber, a siphon and an actuating device therefor operated on the emergency condition of said distributing system to start said siphon, a receiver 45 into which said siphon discharges and provided with an automatically starting discharge device to be operated when a prede- 50 termined charge has entered said receiver and discharge the same therefrom to cause the initial working pressure in said mixing tank.
- 55 29. In fire extinguishing apparatus, a distributing system, a connected supply tank, coöperating siphon means operating on the emergency condition of said system to cause a predetermined working fluid pressure in 60 said tank and means to automatically maintain said pressure substantially constant throughout the discharge of liquid from said tank.
- 65 30. In fire extinguishing apparatus, a supply of extinguishing liquid, coöperating chemical pressure generating means comprising an acid container containing a predetermined charge of pressure generating chemical to generate a substantially predetermined initial pressure, a protecting layer of inert oily material extending over said chemical to prevent undesirable action of the gaseous medium contained in the upper part 70 of said chamber and supplemental pressure generating means to thereafter maintain the working pressure substantially constant.
- 75 31. In fire extinguishing apparatus, chemical pressure generating means comprising a tank containing carbonate extinguishing liquid and a communicating acid chamber having an overflow passage and containing a charge of sulfuric acid and a protecting layer of inert oily material extending over said acid to prevent undesirable action of the gaseous medium in the upper part of said chamber.
- 80 32. In fire extinguishing apparatus, a distributing system, a connected chemical mixing tank charged with carbonate extinguishing liquid, chemical means comprising a siphon and a coöperating acid chamber containing a charge of acid covered with a layer of inert protecting material, a coöperating actuating device operated on the emergency condition of the system to discharge a predetermined charge of said acid into said carbonate liquor to cause the initial working pressure in said mixing tank.
